UNITED STATES PATENT OFFICE.

NILS OLOF SWENSON, OF BROOKLYN, NEW YORK.

DESIGN FOR A SWING-SUPPORT.

SPECIFICATION forming part of Design No. 27,517, dated August 10, 1897.

Application filed April 1, 1897. Serial No. 630,311. Term of patent 14 years.

To all whom it may concern:

Be it known that I, NILS OLOF SWENSON, a subject of the King of Sweden and Norway, and a resident of Brooklyn, in the county of Kings and State of New York, have invented and produced a new and original Design for Swing-Supports, of which the following is a specification.

My design relates to an article of manufacture comprising a swing-support such as may be temporarily set up between the jambs or posts of a door, when the door is open, to suspend the swing therein.

In the accompanying drawing my design is represented in a perspective view of such a support.

The support comprises two strut-blocks and a strut-screw.

The design for the strut-blocks comprises the base *d*, of substantially square form, mid-

dle section *e*, of concavo-conic form, a section *f*, of cylindrical form, and a cap-piece *g*, of circular form and slightly larger than the cylindrical section *f*. The outer extremities of the strut-blocks are formed with a channel *i* across the end diagonally to the square of the base and with projecting studs *j* on the ends.

The portion of the support between the blocks has a bulged middle section *h*.

I claim—

The design for a swing-support substantially as herein shown and described.

Signed at New York city, in the county and State of New York, this 9th day of March, A.D. 1897.

NILS OLOF SWENSON.
